UNITED STATES PATENT OFFICE

COSMO GORDON CALKINS, OF LANSING, MICHIGAN

MONEY SACK

Application filed September 3, 1929. Serial No. 389,900.

The invention relates to improvements in bags, and particularly to an improved money bag or container adapted for holding and transporting currency of various denominations.

It is an object of the invention to provide an improved money bag for carrying currency in such a manner that various denominations placed therein are kept separate.

Another object of the invention is to provide an improved money bag having a plurality of receptacles each of which is readily accessible.

Another object of the invention is to provide an improved container, of the character referred to, which may be folded compactly and securely tied, and which is inexpensive to manufacture and durable in use.

The foregoing and such other objects of the invention as will appear hereinafter as the description proceeds, will be more readily understood from a perusal of the following specification, reference being had to the accompanying drawings, in which:

Fig. 1 is a front elevational view of the improved money bag, showing portions broken away.

Fig. 2 is a vertical central sectional view, taken substantially on line 2—2 of Fig. 1.

Fig. 3 is a fragmentary sectional view through one of the pockets, taken substantially on line 3—3 of Fig. 1.

Fig. 4 is a side elevational view of the money bag shown partially filled and having portions folded over.

Fig. 5 is a side elevational view showing the bag folded and tied.

It is the custom, in large mercantile establishments, department stores, and the like, where cash registers, cash drawers, and other cash holding devices are used, to assemble the daily receipts into a single container for delivery to the main office, accounting department, or bank. The currency taken from each department must be counted before being deposited in the container and it is necessary to separate the various denominations and count the currency upon reaching its destination.

The device embodying the invention, as set

forth herein, obviates the necessity of separating and counting the various denominations of currency each time it is moved from one place to another, thereby saving time and minimizing the possibility of error or loss. 55 Separate compartments or pockets are provided for each of the various denominations and these various compartments are so formed and arranged relative to each other that they are readily accessible for filling or 60 emptying.

Referring to the drawings in detail, the improved container or bag which preferably is made of canvas or other similar material comprises a sack 12 having a plurality of 65 pockets 13 secured thereto. The pockets 13 are adapted to receive coins of different denominations, such as pennies, nickles, dimes, quarters, and half dollars; and bills and checks are deposited in the sack 12. The sack 12 is preferably formed of one piece of material folded, as shown at 14, Fig. 1 and having its joined edges 15 and 16 secured together by stitches 17. It is preferable that the sack 12 be sewed together with the material folded 70 inside out so that the outlets 18 of the seams formed by stitches 17 are disposed inwardly when it is turned right side out. The open end 19 of the sack 12 is preferably reinforced by folding the edges of the material and 75 stitching at 21 to form hems 22.

The pockets 13 are preferably formed of two portions of material forming front and back members 23 and 24 respectively, the portion 24 extending beyond the reinforced edge 25 of the front portion 23 to provide an extension or flap 26. These two sections are joined by stitches 27 on their longitudinal sides and rounded bottom edge, and the 80 seams 28 formed by said stitches preferably are disposed inwardly when the pockets are completed by sewing the material inside out. Hems 29 are provided on the edges of the extensions or flaps 26 as a means of reinforcing them.

The pockets 13 are arranged in superimposed relation with each other on the sack 12 by securing the lateral edge 31 of each of the flaps 26 to one wall of the sack 12 by a 85 double row of stitches 32. A reinforcing

member or strip of material 33 preferably is placed over the joined edges 31 of the flaps 26 and secured in place thereover by the stitching 32. It will be noted, by referring particularly to Figs. 2 and 3, that the various edges of the sack and the pockets are all reinforced by hems or seams, thus a very durable container is provided which will withstand hard usage.

10 It is preferable that the outermost pocket 13 be filled first and access may be had to the next succeeding pocket by swinging the one which has been filled over the top of the sack 12, as shown in Fig. 4, the coins deposited therein remaining in said pocket of their own weight. As each of the pockets 13 are filled they are swung over the top of the sack in the same manner as the first and when all of said pockets are filled they are 15 returned to their original position. Bills or checks are placed in the sack 12 and the upper portion of said sack and the flaps 26 are folded over the pockets 13 and secured in place by a tying strap 34 as shown in Fig. 5. 20 This strap 34 may be detachable or it may be secured by the stitches 21 to one of the hems 22 of the sack. With the container folded and tied in this manner the contents of the sack or pockets can not fall out, irrespective 25 of the position assumed thereby.

The advantage of employing a container for currency as described in the foregoing may be readily appreciated as notes may be kept of the amount of currency placed in 30 each pocket. When the containers from various departments are collected together it is unnecessary to recount the money, thus considerable time is saved and the probability of error or loss is minimized.

40 Although an exemplary form of the invention has been illustrated in the accompanying drawings and described in detail in the foregoing specification, it is to be readily understood that the improved money bag 45 may be made in various sizes and may embody certain variations in detail structure without departing from the spirit of the invention or the scope of the appended claims.

I claim:

50 1. An article of the class described, comprising, a sack formed of one piece of material, a plurality of pockets arranged in superimposed relation on said sack, each of the pockets being formed of two sections of 55 material partially joined together adjacent their edges by stitches, and having its open end disposed toward the open end of said sack, one section of each of said pockets extending beyond the other to form a flap, and 60 said flaps being secured by stitches to the same wall of the sack.

2. An article of the class described, comprising, a sack formed of one piece of material, a plurality of flaps secured along one 65 of their edges by stitches to the outside face

of the same wall of said sack, said flaps overlying each other and having a pocket on their outwardly disposed side, the line of stitches securing the flaps to the sack being below the open end of the latter, whereby 70 said flaps may be folded over said open end to dispose of pockets on the rear side of the sack.

3. An article of the class described, comprising, a sack formed of one piece of material, a plurality of superimposed flaps secured along one of their edges by stitches to the outside face of the same wall of said sack, a pocket formed on the outwardly disposed side of each of said flaps, and means 80 secured to the open end of the sack for securely tying the sack and pockets to prevent displacement of the contents.

In testimony whereof I affix my signature at Detroit, Wayne County, Mich.

COSMO GORDON CALKINS.
